UNITED STATES PATENT OFFICE.

GEORGE F. LYNN, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,317,301.

Specification of Letters Patent. Patented Sept. 30, 1919.

Original application filed July 19, 1917, Serial No. 181,527. Divided and this application filed January 31, 1918. Serial No. 214,764.

To all whom it may concern:

Be it known that I, GEORGE F. LYNN, a citizen of the United States, and resident of Detroit, Wayne county, State of Michigan, have invented certain new and useful Improvements in Hydrocarbon - Motors, of which the following is a specification.

This application is a division of my co-pending application Serial No. 181,527 filed

10 July 19, 1917.

One of the objects of the invention is to form a motor cylinder of particularly light construction while at the same time providing strength and rigidity and ability to 15 withstand high heat.

Other objects of the invention will appear from the following description taken in connection with the drawings which form a part of this specification, and in which:—

20 Figure 1 is an elevation of a drop forged blank from which the cylinder proper of a motor cylinder may be machined;

Fig. 2 is an elevation of a portion of the cylinder blank shown in Fig. 1 after it 25 has been machined;

Fig. 3 is a section on the line 3—3 of Fig. 2;

Fig. 4 is a view similar to Fig. 2 showing the machined flange on the cylinder bent 30 over or downwardly;

Fig. 5 is a section on the line 5—5 of Fig. 4;

Fig. 6 is a perspective view of a two-part anvil or tool used in bending over the flange 35 on the cylinder;

Fig. 7 shows the anvil in position on the cylinder ready to have the flange bent over it;

Fig. 8 is similar to Fig. 7 except that the 40 flange has been bent over the anvil;

Fig. 9 is a vertical section of an inverted cylinder with its jacket thereon ready to be welded;

Fig. 10 is similar to Fig. 9 except that the 45 welding operation has been performed for joining the jacket to the cylinder; and

Fig. 11 is a vertical section of two cylinders 5 joined together with a single jacket around them.

50 For the purpose of obtaining a very strong cylinder, the cylinder proper of this invention is preferably formed from a steel drop forging such as illustrated in Fig. 1. This cylinder blank is indicated at B and it has

a main body portion 20 at the lower end of 55 which is roughly formed a flange 21 and at the upper end of which is a head 22 having suitable bosses 23 and 24 to which other parts of the cylinder may be welded or otherwise secured in making a finished motor 60 cylinder. At a suitable point along the body of the cylinder a radial flange 25 is roughly formed.

It will be understood that the blank shown in Fig. 1 is bored out and the exterior is 65 machined so that a comparatively thin cylinder wall is obtained throughout its length. A portion of the machined cylinder is shown in Fig. 2. The flange 25 thereof is of substantially uniform thickness instead 70 of being tapered as was necessary in the forging. Strengthening ribs 26 are left on the cylinder. If the cylinder is to be used with a separate water jacket, the flange 25 will be the same width throughout, but in 75 Figs. 2 and 3 the flange is extended somewhat on one side of the cylinder as shown particularly at 27 in Fig. 3. This extended part gives an irregular shape to the flange, part of its outer edge being straight at 28 80 and notches 29 are cut in it to assist in bending the flange downwardly as hereinafter described. The thickness of the flange 25 depends largely upon the thickness of the sheet metal water jacket which is to surround the cylinder and to be connected to the flange. It is desirable that the outer part of the flange at least should be substantially the same thickness as the said jacket. The outer part of the flange 25 shown in 85 Figs. 2 and 3 is now bent over or downwardly as shown in Figs. 4 and 5. If the flange is to be circular this shape may be obtained by the original machining operation but with the irregular shape of flange 90 shown in Fig. 5, used to permit two cylinders to be brought closely together, the flange is preferably formed radially as shown in Fig. 2 and then bent over by the use of suitable tools.

Fig. 6 illustrates in perspective a two part tool 30 which may be used for bending over the flange. This tool comprises blocks 31 and 32 pivotally connected together by a link 33 and detachably connected at their 105 other ends by a bolt 34. The upper portions of the blocks form an anvil 35 of the desired shape of the down-turned flange and

these blocks are clamped about the cylinder directly beneath the flange 25 as shown in Fig. 7. In Fig. 8 the flange has been hammered or otherwise bent down over the anvil 35 and the bent portion 36 of the flange forms a skirt to which the sheet metal water jacket above referred to may be secured. The tool 31 may be readily removed from the cylinder after the bending over operation.

In Fig. 9 the cylinder B is shown inverted and a water jacket 37 is shown surrounding the cylinder and the flange 25. The water jacket is in contact with the bent over part 38 of the flange 25 and its extreme end 36 is in juxtaposition to the end of the skirt 36. These two pieces of metal are of substantially the same thickness and they are advantageously positioned for applying a welding heat without too greatly heating the body of the cylinder. In Fig. 10 the welding has been applied at 39 to the ends of the jacket and skirt and those two parts have been welded together.

In Fig. 11, two cylinders B are shown and they are arranged so closely together that the straight part 40 of the skirt 36 of one cylinder is in contact with the straight part of the skirt of the adjacent cylinder. These straight parts of the skirts may be heated and thereby welded together and a single jacket 37^a is then placed around both of the cylinders and welded to the curved parts of the skirts in the manner illustrated in Figs. 9 and 10. The cylinders may also be welded together at their bases where their flanges 25 come together as shown in Fig. 11.

But a single form of the invention is shown and described herein. However it will be understood that other forms and modifications may be made without departing from the spirit or scope of the invention.

Having thus described my invention, what I claim and desire to secure by Letters Patent is:—

1. A motor cylinder block comprising two or more cylinders formed with radial flanges integral with the bodies of the cylinders

ders and having down-turned outer parts forming skirts, portions of the skirts of adjacent cylinders being welded together, and a jacket surrounding said cylinders and said flanges, and welded to the portions of the skirts that are not so connected together.

2. A water jacketed motor cylinder comprising a cylinder proper having a radial flange integral with the body of the cylinder and having an outer bent-down portion forming a depending skirt thereon, a jacket about said cylinder and flange and having its lower end welded to the down-turned skirt of said flange.

3. A motor cylinder block comprising two or more cylinders formed with radial flanges integral with the bodies of the respective cylinders and a water jacket surrounding said cylinders and said flanges, the outer part of the flanges being of substantially the same thickness as the jacket, portions of the flanges of adjacent cylinders being rigidly connected and the unconnected portions being welded to said water jacket.

4. A motor cylinder block comprising two or more cylinders formed with radial flanges having their borders turned down forming skirts, said flanges being irregular in outline, having curved and straight portions, the straight portions of the flanges of adjacent cylinders being welded together, and a jacket surrounding said cylinders and said flanges, and welded to the curved portions of said flanges.

5. A motor cylinder block comprising two or more cylinders formed with radial flanges integral with the bodies of the respective cylinders and of irregular shape, some portions straight and others curved, the borders of said flanges being turned-down to form skirts, the straight portions of the skirts of adjacent cylinders being welded together, and a jacket surrounding said cylinders and said flanges and welded to the curved portions of said skirts.

In testimony whereof I affix my signature.

GEORGE F. LYNN.
